UNITED STATES PATENT OFFICE.

JOHN NEWBERRY REYNOLDS, OF GREENWICH, CONNECTICUT, AND FRANKLIN A. STEARN, OF PATERSON, NEW JERSEY, ASSIGNEES TO WESTERN ELECTRIC COMPANY, INCORPORATED, OF NEW YORK, N. Y., A CORPORATION OF NEW YORK.

TELEPHONE SYSTEM.

1,340,982.

Specification of Letters Patent. Patented May 25, 1920.

Application filed December 29, 1916. Serial No. 139,539.

To all whom it may concern:

Be it known that we, JOHN NEWBERRY REYNOLDS and FRANKLIN A. STEARN, citizens of the United States, residing at Greenwich, in the county of Fairfield and State of Connecticut, and at Paterson, in the county of Passaic and State of New Jersey, respectively, have invented certain new and useful Improvements in Telephone Systems, 10 of which the following is a full, clear, concise, and exact description.

This invention relates to telephone systems, and more particularly to circuit arrangements for controlling the operation of 15 selectively operable switching devices employed in automatic telephone exchanges.

In the automatic telephone systems now employed for controlling the transmission of revertive impulses, *i. e.*, impulses by 20 which the operation of the selector switches is determined in accordance with the setting of a sender of the impulse receiving type, it is necessary to provide, on the selector switch, commutators having 25 properly spaced conducting segments corresponding in number to the number of groups of trunks served by the switch.

At present, if it is desired to vary the number of trunks in a group it is necessary to 30 provide a new commutator having its conducting segments differently spaced. In order to avoid this changing of commutators, according to the present invention, certain 35 of the test terminals in the terminal bank are used for controlling the transmission of impulses to the sender. The test terminals, so used, may define the limits of a group of trunks and are electrically distinguished from the test terminals associated with the 40 trunk lines within the respective group.

In automatic telephone systems of the above described type a stepping relay is employed to control the operation of the sender in accordance with the impulses received from the selector. This stepping relay is alternately rendered effective and ineffective by a shunt circuit completed during the operation of the switch. In the present arrangement it is proposed to open and 45 close the operating circuit of said stepping relay under the control of the switch instead of short-circuiting the stepping relay as formerly. This proposed change is advantageous, since it causes the stepping relay

to release or retract its armature more 55 quickly than under the former arrangement.

In the present system the sequence switches employed are of a structure similar to that disclosed in the patent to Reynolds and Baldwin, No. 1,127,808, and are similar in 60 operation and function to that disclosed in the patent to McBERTY, No. 1,125,579.

The selector switches employed in the system are similar in structure to the switch disclosed in patent to Craft and Reynolds, 65 No. 1,123,696, January 5, 1915. The operating circuit for these switches is fully disclosed in the patent to Lundell, No. 1,168,319, January 18, 1916.

In the system, as actually used, registers 70 and controlling devices of the structure and arrangement disclosed in Lundell Patent No. 1,168,319, above mentioned, are employed. Since the operation and arrangement of these registers and the manner in which they 75 are controlled, form no part of this invention, the registers have been omitted, and it has been assumed that the operator will depress certain keys of her key-set to control the actuation of the proper counting relay 80 of the series.

The drawings, with Figure 2 placed below Fig. 1 and with Fig. 3 placed below Fig. 2, 85 diagrammatically represent a portion of a semi-automatic telephone system embodying the present invention.

When the subscriber, located at the substation indicated at 100, removes his receiver from the switchhook, a circuit is closed from the minus pole of battery, through the left-hand winding of relay 106, outer armature and back contact of cut-off relay 107, through the substation apparatus, inner back contact and armature of cut-off relay 107 and the right-hand winding of line 90 relay 106, to the plus pole of battery. The line relay 106 attracts its armature and thereby completes a local circuit for lighting the lamp 108. The operator, on noting that the lamp is lighted, inserts an answering plug 109 into the answering jack 110 of the calling line. The cut-off relay 107 and the relay 111 are thereupon energized in series over a circuit extending from ground 100ed battery, winding of cut-off relay 107, 105 sleeve of the jack 110, sleeve of the plug 109, winding of relay 111, to ground. These relays attract their armatures and the cut-off

relay interrupts the energizing circuit of the line relay, which, on retracting its armature, interrupts the circuit of the lamp 108. The relay 111 completes a circuit from ground, its armature and front contact, contact 112 and the magnet of a sequence switch 113, to grounded battery, to move the sequence switch out of position 1. Under the control of its normal contact 148 the sequence switch moves into position 2. In position 2 of sequence switch 113, a circuit is completed from ground, through contact 114, conductor 115, contacts 202 and 203 of sequence switch 200, winding of relay 204, to grounded battery. The relay 204 establishes through its left-hand armature a locking circuit for itself, which extends from grounded battery, winding of the relay 204, its left-hand front contact and armature, conductor 205, conducting portion of the commutator 206, commutator brush 207, to ground. At its right-hand armature the relay 204 closes a circuit from grounded battery, magnet of sequence switch 200, contact 208, right-hand front contact and armature of relay 204, to ground, to move the sequence switch into position 2. In position 2 of sequence switch 200 relay 204 is maintained energized over a circuit extending from grounded battery, the winding, left-hand front contact and armature of relay 204, contacts 242' and 242, back contact and armature of relay 214, to ground and over a parallel circuit completed through commutator 206 and brush 207. A circuit is also completed at this time for the up-drive magnet 209 for elevating the cord-finder 210 to associate an idle sender with the cord circuit, now connected to the calling line. The energizing circuit of the up-drive magnet 209 extends from grounded battery, winding of up-drive magnet 209, contact 211, right-hand front contact and armature of relay 204, to ground. The cord-finder elevates its brushes, under the control of the up-drive magnet 209, until brush 212 encounters contact 213, whereupon relay 214 is energized over a circuit extending from ground, winding of relay 214, contact 215, cord-finder brush 212, terminal 213, conductor 216, contact 116, to ground. The relay 214 attracts its armature and at its right-hand armature establishes a locking circuit for itself which is maintained until the sequence switch 113 moves out of position 11. This circuit may be traced from grounded battery, winding of relay 214, contact 217, right-hand front contact and armature of relay 214, brush 218, terminal 219, conductor 220, contact 117, to ground. At the left-hand armature and back contact of relay 214, one of the energizing circuits of the relay 204 is interrupted, and when the cord-finder has accurately centered its brushes on the proper set of

terminals, the locking circuit for the relay 204 will be interrupted by reason of the commutator brush 207 engaging an insulated segment of the commutator 206. The relay 204 retracts its armatures and thereby 70 opens the circuit of magnet 209, and completes a circuit for moving sequence switch 200 out of position 2 and into position 3. This circuit is established from grounded battery, magnet of the sequence switch 200, 75 contact 221, right-hand back contact and armature of relay 204 to ground.

When the sequence switch 200 reaches position 3 a circuit is completed from ground, contact 223, conductor 224, contact 304, 80 magnet of sequence switch 300, to grounded battery to move the sequence switch 300 out of position 1 and into position 3.

While these operations have been taking place the operator depresses her listening-in key 118 to telephonically connect her head-set 119 with the calling subscriber's substation apparatus. She thereupon ascertains the number of the desired line and proceeds to set up this number on the key-set indicated at the right of Fig. 3. The combination of number keys depressed determines the apparatus and link-circuit that will be employed in interconnecting the calling substation 100 and the called substation 156. 85 90 95

The operator, after depressing the proper keys of the key-set, operates the start key 302, which closes a circuit for moving the sequence switch 200 into position 4. This 100 circuit may be traced from grounded battery, magnet of the sequence switch 200, contact 222, conductor 303, start key 302, to ground. Simultaneously a circuit is completed for moving the sequence switch 300 105 out of position 3 into position 4. This circuit is established from grounded battery, magnet of the sequence switch 300, contact 305, start key 302, to ground.

With the sequence switch 113 in position 110 2, sequence switch 200 in position 4, and sequence switch 300 in position 4, a fundamental circuit is established from grounded battery, line relay 120, contact 121, conductor 123, contact 124, conductor 125, terminal 229, brush 228, conductor 309, outer armature and back contact of upper zero counting relay 308, windings of the stepping relay 307, contact 306, conductor 227, brush 226, terminal 225, conductors 230 and 126, 115 120 contact 127, commutator brush 128, commutator 129, to ground. The line relay 120 attracts its armatures and at its left-hand front contact and armature completes a locking circuit for itself through the contact 125 130, over the circuit described, to ground at commutator 129. At the right-hand front contact and armature of relay 120, a circuit is completed for moving sequence switch 113 125 out of position 2, and into position 3. This 130

circuit is completed from grounded battery, magnet of the sequence switch 113, contact 131, right-hand front contact and armature of relay 120, to ground. In position 3 of the sequence switch 113, a circuit is prepared from grounded battery, winding, left-hand front contact and armature of relay 120, contacts 130 and 132, commutator brush 133. Simultaneously a circuit is established for the up-drive magnet 134, which circuit may be traced from grounded battery, winding of magnet 134, contact 135, right-hand front contact and armature of relay 120, to ground. The district selector switch 136 10 now elevates its brush shaft under control of the up-drive magnet 134. As the brush shaft of the district selector switch 136 is elevated, the circuit completed through the commutator brush 128 is opened and, upon 15 the engagement of the commutator segment by brush 133, the circuit prepared for relay 120 is closed. The conducting portion of the commutator 129 is so prepared that either the brush 128 or the brush 133 are in 20 engagement with the conducting portion of the commutator, and for this reason the circuits controlled by these brushes are alternately closed and opened. The line relay 120 is thus maintained energized, and the 25 fundamental circuit, above described, is opened and closed to actuate a series of counting relays, the number of which depends upon which one of the keys 310 controlling the district brush selection have 30 been depressed. When the series of counting relays has been actuated by impulses transmitted under the control of commutator 129, the upper zero counting relay 308 is 35 energized. The relay 308 attracts its armature and at its outer armature and back contact interrupts the fundamental circuit. As soon as the brush 133 leaves the conducting plate 129, the line relay 120 becomes deenergized. At the inner armature and front 40 contact of the relay 308, a circuit is completed from grounded battery, magnet of the sequence switch 300, front contact and inner armature of relay 308, contact 311, to ground, to move sequence switch into position 6. The counting relays which were 45 locked up become deenergized.

With the line relay 120 deenergized there is completed a circuit for moving sequence switch 113 into position 4. This circuit is 50 established from grounded battery, magnet of sequence switch 113, contact 137, right-hand contact and armature of relay 120, to ground. In position 4 of sequence switch 113, brush tripping magnet 169 is energized 55 over a circuit extending from grounded battery, magnet 169, contact 170, to ground. Magnet 169 causes the tripping of the desired set of brushes in the well-known manner. Simultaneously, the fundamental circuit 60 is reestablished from grounded battery,

winding of the relay 120, contact 121, conductor 123, contact spring 138 of polarized relay 139, conductor 140, contact 141, conductor 125, terminal 229, brush 228, conductor 309, outer armature and back contact of the relay 308, stepping relay 307, contact 306, conductor 227, brush 226, terminal 225, conductors 230 and 126, contact 142, to ground. Line relay 120 attracts its armatures and at its left-hand armature and front contact completes a locking circuit for itself through the contact 130, over the fundamental circuit described, to ground at contact 142. At the right-hand armature and front contact of relay 120, a circuit is completed from ground, contact 131, magnet of the sequence switch 113, to grounded battery, to move this sequence switch out of position 4 into position 5. In position 5, the operating circuit for the up-drive magnet 134 is again completed from grounded battery, winding of the magnet 134, contact 135, right-hand front contact and armature of relay 120, to ground. The district selector switch 136, under the control of the up-drive magnet 134, again elevates its brushes.

In accordance with this invention, the reverte impulses for controlling the group selection at the selector switch are controlled, not by a special commutator, but by test terminals in the terminal bank of the switch. By reason of employing test terminals of the terminal bank to control the group of varied impulses it is possible to readily increase, or diminish, the number of trunks in a group without resorting to a special type of commutator.

It should be stated that the test terminals of idle trunks are connected to battery and the test terminals of busy trunks are connected to ground through a resistance of approximately one hundred ohms, while the test terminals that are employed to control the sending of reverte impulses are connected directly to ground. A polarized relay 139 employed in controlling the group selection of the selector switch is marginal and will not operate when a resistance of one hundred ohms is included in its energizing circuit.

As the selector switch 136 elevates its brushes 143, 144 and 145, the test brush 145 encounters the test terminal 146, which is connected directly to ground. When the test brush 145 encounters the test terminal 146, the polarized relay 139 is energized over a circuit extending from grounded battery, the windings of this relay, contact 147, test brush 145, contact 146, to ground. The polarized relay 139 in this instance attracts its armature and interrupts the fundamental circuit previously traced, and simultaneously completes a circuit for maintaining the line relay 120 energized. This circuit is established from ground, armature of the

relay 139, contact spring 138, conductor 123, contact 130, left-hand front contact and winding of the relay 120 to grounded battery. Since the circuit of the stepping relay 307 is interrupted, this relay retracts its armature to control the actuation of the counting relays in the well-known manner. When the selector switch 136 has been elevated to hunt over a number of groups of 10 trunks sufficient to transmit impulses controlling the district group selection as determined by the depressed district group key 312, the upper zero counting relay 308 is energized and attracts its armatures. At 15 its outer back contact and armature, the fundamental circuit previously described is interrupted, causing the line relay 120 to deenergize. At the inner armature and front contact of the relay 308, a circuit is 20 completed for moving the sequence switch 300 out of position 6 and into position 8. This circuit extends from grounded battery, magnet of sequence switch 300, front contact and inner armature of relay 308, contact 311 to ground. When the line relay is 25 deenergized a circuit is completed from ground, the right-hand armature and back contact of relay 120, contact 137, sequence switch 113 to grounded battery, for moving 30 the sequence switch out of position 5. The sequence switch continues to rotate by reason of a circuit completed through its master contact 148, until it reaches position 11. The trunk hunting operation of the district 35 selector switch 136 has been omitted, since it forms no part of this invention. It will be understood, however, in the normal operation of the system, that this trunk hunting operation takes place in position 7 of 40 the sequence switch 113.

It is assumed that the trunk hunting operation has taken place and that the selector brushes 143, 144 and 145 have been placed in engagement with the trunk terminals 149, 45 150 and 151 to extend the calling line to the incoming selector switch indicated by the brushes 152 and 153. When the proper brush and group of trunks have been selected at the incoming selector switch, as determined by the depressed incoming brush key 313 and the incoming group key 314, the 50 trunk hunting operation to select an idle trunk to the final selector takes place in the well-known manner. It will be noted that 55 after the transmission of each series of impulses, the sequence switch 300 is advanced in the manner above described.

The final selector switch, which is indicated by the brushes 154 and 155, first 60 selects a proper brush which will engage with any line of the group in which the desired line terminates. This brush selection is determined by the depression of one of the final brush keys 315. The switch then 65 operates under the control of the tens and

units keys 316 and 317 to connect the calling substation 5 with the called substation 156.

It will be understood that, in the operation of setting the incoming and final selector switches, the fundamental circuit is 70 opened and closed in the same manner as disclosed in the description of the district selector switch for controlling the operation of the counting relays. The general structure of the conducting portion of the commutator associated with the incoming and final selector switches is similar to that of the conducting portion of commutator 129, the size of the commutators being dependent 75 upon the maximum number or character of 80 selecting operations desired.

At the close of the units series of impulses, when the upper zero counting relay is energized, the sequence switch 300 is rotated out of position 16 by means of a circuit established from grounded battery, magnet of sequence switch 300, front contact and inner armature of relay 308, contact 311, to ground. Sequence switch 300 85 continues to rotate until it reaches its normal position by reason of a circuit completed through its master contact 318. When the sequence switch is rotating 90 through positions 17 and 18, a circuit is 95 completed from ground, contact 319, conductor 320, magnet of sequence switch 200 to grounded battery, to move the sequence switch from position 4 into position 8. As soon as the sequence switch 200 reaches position 8, an energizing circuit, for moving the sequence switch 113 out of position 11 100 and into position 16, is completed from grounded battery, magnet of sequence switch 113, contact 157, conductor 158, terminal 232, brush 233, contact 234, to ground. In position 8 of sequence switch 200, a circuit is also completed for the down-drive magnet 235, which circuit may be traced 105 from grounded battery, winding of magnet 235, contact 321, conductor 322, contact 236 to ground. When the cord finder 210 has been restored to its normal position, a circuit is completed for restoring the sequence switch 200 to its normal position. This 110 circuit may be traced from grounded battery magnet of sequence switch 200, contact 237, conducting segment 239 of the commutator, commutator brush 240 to ground. 115

At the close of the conversation, the supervisory relays 159 and 160 operate in the well-known manner to indicate to the operator that the call has been terminated. The operator thereupon removes the plug 120 109 from the jack 110 and causes the relay 111 to retract its armature. A circuit is now 125 completed for moving the sequence switch 113 out of position 16, which circuit extends from grounded battery, magnet of sequence switch 113, contact 161, back contact and ar- 130

mature of relay 111 to ground. The sequence switch 113 continues to rotate until it reaches position 18 by reason of a circuit completed through its master contact 148.

5 When the sequence switch reaches position 18 a circuit is closed from grounded battery, winding of the down-drive magnet 162, contacts 163 and 142 to ground. When the district selector has been restored to its normal position, a circuit is completed from grounded battery, magnet of sequence switch 113, conductor 164, contact 165, normal segment 166 of the commutator, commutator brush 167 to ground, to move the 15 sequence switch 113 into its normal position.

When the sequence switch 113 moved out of position 16, the incoming selector switch, which was held actuated over a circuit completed through contact 168, was permitted 20 to release. The release of the final selector switch then takes place in the well-known manner.

What is claimed is:

1. In a telephone system, an incoming 25 line, outgoing lines, a switch for interconnecting said incoming line with any of said outgoing lines, movable brushes for the said switch, fixed terminals associated with said outgoing lines arranged to be engaged by 30 said brushes, a fundamental circuit, a stepping relay and a contact in said circuit, and means controlled by the successive engagement of one of said brushes with certain of said fixed terminals for opening and closing 35 said circuit at said contact.

2. In a telephone system, an incoming line, outgoing lines, a switch for interconnecting said incoming line with any of said outgoing lines, movable brushes for the said 40 switch, fixed terminals associated with said outgoing lines arranged to be engaged by said brushes, a controlling circuit for said switch having branches and means controlled by the engagement of one of said 45 brushes with certain of said fixed terminals for simultaneously opening one of said branches and closing another of said branches.

3. In a telephone system, an incoming 50 line, outgoing lines, a switch for interconnecting said incoming line with any of said outgoing lines, a controlling circuit for said switch, branches for said circuit, a magnet included in a common portion of said circuit, and means controlled by said switch 55 for simultaneously opening one of said branches and for closing another of said branches.

4. In a telephone system, an incoming 60 line, outgoing lines, a switch for interconnecting said incoming lines with any of said outgoing lines, movable brushes for the said switch, fixed terminals associated with said outgoing lines arranged to be engaged by 65 said brushes, a variably controlled device

arranged to govern the setting of said switch and means including one of said movable brushes and said fixed terminals for producing a series of impulses to control said device.

5. In a telephone system, an incoming line, outgoing lines, a switch for interconnecting said incoming line with any of said outgoing lines, movable brushes for the said switch, fixed terminals associated with said outgoing lines arranged to be engaged by 70 said brushes, a variably controlled device arranged to govern the setting of said switch and means controlled by one of said movable brushes for transmitting a series 75 of impulses to operate said device.

6. In a telephone system, an incoming line, outgoing lines, a switch for interconnecting said incoming line with any of said outgoing lines, movable brushes for the said 80 switch, fixed terminals associated with said outgoing lines arranged to be engaged by said brushes, some of said fixed terminals being electrically distinguished from others of said fixed terminals, a variably controlled 85 device arranged to govern the setting of said switch and means operative in response to the engagement of certain fixed terminals by one of said brushes for producing a series of impulses for actuating said device. 95

7. In a telephone system, an incoming line, outgoing lines, a switch for interconnecting said incoming line with any of said outgoing lines, a variably controlled device for governing the setting of said switch, 100 means including a polarized relay for controlling the operation of said device, and a circuit for said polarized relay controlled by said switch.

8. In a telephone system, a selector switch 105 having movable and stationary contacts, a motor magnet for said switch, a relay for controlling the operation of said magnet, a circuit for said relay, a sending device for controlling said circuit, two branches 110 for said circuit, means controlled by said switch for controlling one of said branches, another relay for controlling the other branch, means responsive to the engagement of certain of said stationary contacts 115 by said movable contacts for operating said last-mentioned relay, and means responsive to the control of either one of said branches for operating said sending device.

9. In a telephone system, an incoming 120 line, outgoing lines, a variably operable switch for interconnecting said incoming line with any of said outgoing lines, a device arranged to govern the setting of said switch, an operating circuit for said device, a polarized relay, means for operating said polarized relay during certain operations of said switch to control the operating circuit of said device. 125

10. In a telephone system, an incoming 130

line, outgoing lines, a switch for interconnecting said incoming line with any of said outgoing lines, said switch being provided with movable brushes and fixed terminals, 5 a counting device arranged to govern the setting of said switch, an operating circuit for said device, a polarized relay controlling said circuit, and a circuit for said polarized relay closed through certain of 10 said movable brushes and certain ones of said fixed terminals.

11. In a telephone system, an incoming line, outgoing lines, a switch for interconnecting said incoming line with any of said 15 outgoing lines, a test brush for said switch, a fundamental circuit, a stepping relay and a contact in said circuit, and means controlled by said test brush for successively interrupting said circuit at said contact.

12. In a telephone system, an incoming line, outgoing lines, a switch for interconnecting said incoming line with any of said outgoing lines, movable brushes for the said switch, fixed terminals associated with said 25 outgoing lines arranged to be engaged by said brushes, some of said fixed terminals being electrically distinguished from others of said fixed terminals, a fundamental circuit, a stepping relay and a contact included 30 in said circuit, and means operative in response to the engagement of certain fixed terminals by one of said brushes for successively interrupting said circuit at said contacts.

13. In a telephone system, an incoming 35 line, outgoing lines, a switch for interconnecting said incoming line with any of said outgoing lines, a test brush for said switch, fixed terminals associated with said outgoing lines and arranged to be engaged by said 40 brush, other terminals arranged to be engaged by said brush, a variably controlled device arranged to govern the setting of said switch, and means including said test brush and said last mentioned terminals for 45 controlling said device.

14. In a telephone system, an incoming line, outgoing lines, a switch for interconnecting said incoming line with any of said outgoing lines, a test brush for said switch, 50 a series of fixed terminals arranged to be engaged by said brush, certain of said terminals being associated with said outgoing lines and being variously electrically characterized to indicate the busy and idle condition of said outgoing lines, others of said terminals being electrically distinguished from the first mentioned terminals of said series, a variably controlled device arranged to govern the setting of said switch, and 55 means including said test brush and the last mentioned terminals of said series for controlling said device.

In witness whereof we hereunto subscribe our names this 28th day of December, A. D. 65 1916.

JOHN NEWBERRY REYNOLDS.
FRANKLIN A. STEARN.
